CLAIM

The ornamental design for a belted towel, as shown and described.

DESCRIPTION

FIG. 1 is a front perspective view of a belted towel, illustrating my new design;

FIG. 2 is a front perspective view of a belted towel as it would appear in use wrapped around a person or object;

FIG. 3 is a front plan view of a belted towel of my design;

FIG. 4 is rear plan view of thereof;

FIG. 5 is top plan view thereof;

FIG. 6 is left end plan view thereof;

FIG. 7 is right end plan view thereof; and,

FIG. 8 is a bottom plan view thereof.

The broken lines shown in FIGS. 1, 2, 3 and 4 represents

portions of the towel that form no part of the claimed design. The broken lines on the belt represent stitching that does not form part of the claimed design.
